DESIGN FOR A FOLDING HOUSE VEHICLE OR SIMILAR ARTICLE

Nettie E. Graven, Wooster, Ohio

Application October 17, 1945, Serial No. 122,921

Term of patent 14 years

(Cl. D14—3)

To all whom it may concern:

Be it known that I, Nettie E. Graven, a citizen of the United States, residing at Wooster, in the county of Wayne and State of Ohio, have invented a new, original, and ornamental Design for a Folding House Vehicle or Similar Article, of which the following is a specification, reference being had to the accompanying drawing, forming part thereof.

Figure 1 is a top plan view of a folding house vehicle in expanded or unfolded position, showing my new design;

Fig. 2 is a side elevational view; and

Fig. 3 is a front elevational view thereof.

The side opposite to that shown in Fig. 2 is substantially the same as that shown except for the entrance platform and door, and the rear panels of the body portion are the same as shown in the front view of Fig. 3.

I claim:

The ornamental design for a folding house vehicle or similar article, substantially as shown and described.

NETTIE E. GRAVEN.
